UNITED STATES PATENT OFFICE.

MINOTT W. SEWALL, OF NEW YORK, N. Y., ASSIGNOR TO THE BABCOCK & WILCOX COMPANY, OF BAYONNE, NEW JERSEY, A CORPORATION OF NEW JERSEY.

BOILER-FURNACE.

1,136,175.

Specification of Letters Patent. Patented Apr. 20, 1915.

Original application filed May 27, 1912, Serial No. 699,360. Divided and this application filed November 26, 1912. Serial No. 733,584.

To all whom it may concern:

Be it known that I, MINOTT W. SEWALL, a citizen of the United States, residing at New York city, borough of Manhattan, in the county of New York and State of New York, have invented certain new and useful Improvements in Boiler-Furnaces, of which the following is a specification.

The present application is a division of my application Serial No. 699,860, filed May 27, 1912 upon which Patent No. 1,064,175 has been granted dated June 10, 1913. In that application I have described certain improvements upon the furnace constructions shown in my Patents Nos. 983,000 and 983,170 granted January 31, 1911. In the constructions shown in said patents the greater part of the dust that passes over from the furnace naturally falls to the floor 20 behind the bridge wall. It is there subjected to the reflection of the heat and becomes fused into a solid mass on the floor of the pit. This mass is very difficult to remove, as when cold it is a solid mass of clinker. If 25 the pit is made of sufficient depth, so that the temperature at the bottom is not sufficient to fuse the dust, the latter may be easily removed. If, however, it is allowed to build up too near the top of the bridge 30 wall, the surface of it becomes fused and becomes a solid mass as before mentioned. This is a real difficulty, and one that is not easily overcome without considerable expense in construction and attention in operation.

Several arrangements have been used by different makers of chain grates to cover the rear end of the grate and, at the same time to pass any unburned carbon over the 40 covering parts and discharge them behind the grate on either an auxiliary dumping grate or a dumping plate. Some of these arrangements have been made in the form of a hollow casting which covers the top of the rear of the grate and is formed with a slope toward the front of the grate so as to permit the unburned carbon to pass over it easily. This casting was filled with water so as to prevent its burning out. Other arrangements have been made having solid 50 covering plates or bars tapered toward the front. These have been made of various grades of iron and steel, the efforts having

been to obtain metals which would melt only at a high temperature. All of these have 55 been more or less successful, but have failed under severe working conditions. Other arrangements have been tried in the form of thin bars which act as a continuing solid grate surface. These also will endure for a 60 while but fail under hard service.

The necessity of having some means of allowing the ash to pass over the rear of the grate and at the same time prevent unburned carbon from passing over has led 65 to the adoption of a water back, such as shown in my Patent No. 941,657 granted November 30, 1909. A brick bridge wall is also sometimes used to compact the ash and permit the fire to pass under. This is, however, a very inefficient arrangement. Either the water back as mentioned or the brick construction permits a certain amount of unburned carbon to pass over the rear of the 70 grate, which carbon falls into the ashpit. If 75 the ashpit is not cleaned at proper intervals the carbon and ash fill the pit and burn, and such a temperature is produced that the rear of the grate is heated to a detrimental degree. In order to prevent this heating, I 80 have designed a stripper to be used in combination with a water bridge wall, or with a brick bridge wall, as mentioned. This stripper extends from approximately the tangent point of the rear curve of the grate 85 downwardly and causes any ash or unburned carbon to pass over it into a pit behind the grate and does not permit the ash to pass into the space under the grate. The pit behind the grate may be simply an ashpit or 90 it may contain a grate on which the ash and unburned carbon may fall and remain there until the carbon is burned out, the ash being removed periodically. In said Patent No. 941,657, a rectangular box is shown. The 95 form of this vessel, however, is not essential, and it may be either round or rectangular as may be convenient in construction.

The invention will be understood by reference to the accompanying drawings, in 100 which—

Figure 1 is a vertical longitudinal section; Fig. 2, a sectional plan view on the plane of line 2—2 of Fig. 1; the left-hand portion of Fig. 3, a vertical cross-section on the plane 105 of the line 3—3 of Fig. 1, the right-hand

portion of Fig. 3, a cross-section on the plane of the line 3'-3' of Fig. 1; and Fig. 4 is a view of an enlarged portion of the parts at the rear of the stoker.

5 Similar reference numerals indicate similar parts in the several views.

Referring to the drawings, the numeral 1 designates the boiler casing, in the upper part of which are located the heating surfaces and other parts of a boiler not here shown. In my said Patent No. 1,064,175 I have described the side tubes 2, and their connection with the water circulation through the manifolds 3 and 4. At the rear 15 of the traveling grate 5 is a water box 6, and extending along both side walls approximately at the grate level, are water boxes 7. A second cross box 8 is placed above the box 6, and these two boxes form 20 the bridge wall of the furnace. The water supply for this box system is from the rear manifolds 3 through tubes 9, the forward ends of said tubes entering the under side of box 6 near its ends. Box 8 receives its water 25 supply from box 6 through nipples 10 near the center of said boxes. The side boxes 7 receive their supply from box 6 through nipples 11, and their water discharge is through two pipes 12 at their forward or 30 elevated end, into a box, not shown. Box 8 has its discharge through pipes 13 into the front manifolds 4, and also through pipes 15 into a box, not shown.

Immediately to the rear of box 6, and extending toward the mud drum 16 I have introduced a screen of water tubes 17. This screen extends across the furnace, the ends of the tubes 17 being expanded into the manifolds 18 and 19, the latter being at a 35 higher level than the former in order to give an inclination to the tubes 17. The water supply to manifold 18 enters from one of the manifolds 3 through nipple 20, the circulation passing through tubes 17 40 into manifold 19, and from the latter into box 8 through a nipple 21.

It will be seen that I have modified the furnace of my said Patent No. 983,000 by introducing a screen of water tubes behind 45 the bridge wall, which will largely prevent the reflection of the heat from the combustion chamber downward into the pit behind the bridge wall.

For the purpose of passing the ash and 50 fuel refuse over the rear end of the grate 5 I provide a shield or stripper 22 extending preferably from approximately the rear edge of the water box 6, or approximately the tangent point of the curve of the grate. 55 It is, however, not absolutely essential that this shield should reach as high on the grate as above stated, as a partial protection of the grate may be secured by having the upper edge of the shield as low, or perhaps 60 lower, than the center of the sprocket shaft,

one purpose of the shield being to conduct the ash and fuel refuse which pass under the bridge wall over the top of the shield away from the grate, and thus to prevent hot or burning material being discharged 70 under the grate.

For the purpose of effecting complete combustion of any unconsumed carbon which may be discharged over the rear of the grate, I provide an auxiliary furnace 75 having a grate or floor 23, one of the side walls of this furnace chamber providing a convenient means to which the shield or stripper 22 may be secured, as shown in Fig. 4. The products of combustion from this auxiliary furnace pass directly up between the tubes 17 and mingle with the products of combustion from the furnace proper. An ash receiver 24 will receive the ash from the auxiliary furnace, said receiver being made air-tight with a controllable air entrance 25. A receiver 26 below the traveling grate receives any fine coal that may leak through the grate. This means of disposing of the ash and fuel refuse prevents the heating of the rear of the traveling grate and thereby obviates the objections before noted.

What I claim and desire to secure by Letters Patent of the United States is:—

1. A boiler furnace having a traveling grate, a bridge wall above the grate at the rear, a shield in proximity to the rear curvature of the grate, a pit for the ash and fuel refuse which is discharged between the 100 grate and the bridge wall over said shield, and a series of water tubes forming a shield for said pit for the purpose described.

2. A boiler furnace having a grate, a pit at the rear of the grate, means for discharging the ash and fuel refuse from the grate into said pit, and a series of water tubes forming a shield over said pit for the purpose described.

3. A boiler furnace having a grate, a pit 110 at the rear of the grate below the rear of the furnace combustion chamber, means for causing the ash and fuel refuse to discharge from the grate into said pit, and a series of water tubes forming a shield over said pit, 115 said tubes being connected with the boiler circulation.

4. A boiler furnace having a grate, a bridge wall, a pit at the rear of the grate, means for causing the ash and fuel refuse 120 to pass under the bridge wall and beyond the grate into said pit, and a series of water tubes forming a screen above said pit for the purpose described.

5. A boiler furnace having a traveling 125 grate, a water-box bridge wall above the grate at the rear, a shield or stripper extending from the rear curve of the grate downwardly, a pit beyond the grate for the ash and fuel refuse discharged between the 130

grate and bridge wall over said shield, a wall separating the pit from the space beneath the grate, means for supporting the unburned fuel in the pit, and a heat-absorbing member located between the pit and steam generator.

In testimony whereof I have hereunto

signed my name in the presence of two subscribing witnesses.

MINOTT W. SEWALL.
